(57) CLAIM

The ornamental design for a fragrance bottle, as shown and described.

DESCRIPTION

FIG. 1 is a front perspective view of a fragrance bottle showing my new design;

FIG. 2 is a front view thereof;

FIG. 3 is a back view thereof;

FIG. 4 is a left side view thereof;

FIG. 5 is right-side view thereof;

FIG. 6 is a top view thereof;

FIG. 7 is a bottom view thereof; and,

FIG. 8 is an exploded front perspective view thereof. The broken lines depict the portions of the fragrance bottle that form no part of the claimed design.

1 Claim, 6 Drawing Sheets
